US00D784384S

(12) **United States Design Patent** (10) Patent No.: **US D784,384 S**
 Hong et al. (45) Date of Patent: ** Apr. 18, 2017

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Seongkook Hong**, Seoul (KR); **Jinwoo Choi**, Seoul (KR); **Cheolhoon Kang**, Seoul (KR)

(73) Assignee: **SAMSUNG ELECTRONICS CO., LTD.**, Gyeonggi-Do (KR)

(**) Term: **15 Years**

(21) Appl. No.: **29/547,313**

(22) Filed: **Dec. 2, 2015**

(30) **Foreign Application Priority Data**

Sep. 2, 2015 (KR) 30-2015-0044293

(51) **LOC (10) Cl.** **14-04**

(52) **U.S. Cl.**

USPC **D14/486**

CLAIM

We claim, the ornamental design for a display screen or portion thereof with graphical user interface, as shown and described.

DESCRIPTION

The sole FIGURE is a front view of a display screen or portion thereof with graphical user interface showing our new design.

The broken line showing of the alphanumeric characters, symbols, and display screen in the FIGURE is for environmental purposes only and forms no part of the claimed design.

1 Claim, 1 Drawing Sheet
